(57) **CLAIM**

The ornamental design for a one-piece garment with integral bib, as shown and described.

DESCRIPTION

FIG. 1 is a front elevation view of a one-piece garment with integral bib, showing my new design with a bib in a closed configuration;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front perspective view thereof;

FIG. 8 is a rear perspective view thereof;

FIG. 9 is a front elevation view the one-piece garment with integral bib, showing the bib in an open configuration;

FIG. 10 is a left side elevation view thereof showing the bib in the open configuration;

FIG. 11 is a right side elevation view thereof showing the bib in the open configuration;

FIG. 12 is a top plan view thereof showing the bib in the open configuration;

FIG. 13 is a bottom plan view thereof showing the bib in the open configuration;

FIG. 14 is a front perspective view thereof showing the bib in the open configuration; and,

FIG. 15 is a rear perspective view thereof showing the bib in the open configuration.

The broken lines in the drawings illustrate portions of the one-piece garment with integral bib that form no part of the claimed design.

1 Claim, 15 Drawing Sheets
